(57) **CLAIM**

The ornamental design for a vaporizer power unit, as shown and described.

DESCRIPTION

FIG. 1 is a top, front perspective view of a vaporizer power unit showing our new design;
FIG. 2 is a left side view thereof;
FIG. 3 is a front side view thereof;
FIG. 4 is a right side view thereof;
FIG. 5 is a rear side view thereof; and,
FIG. 6 is a top view thereof.

In FIG. 6 the evenly spaced broken circular line represents a boundary of the design and forms no part thereof; The broken lines consisting of dash-dot-dash lines in the drawings depict aspects of the vaporizer power unit that form no part of the claimed design.
